(57) **CLAIM**

The ornamental design for a container for a confectionery, as shown and described.

DESCRIPTION

FIG. 1 is a front right perspective view of a first embodiment of a container for a confectionery showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a front perspective view of the container for a confectionery of FIG. 1, showing a portion of the lid portion thereof in an alternate position; FIG. 9 is a front right perspective view of a second embodiment of a container for a confectionery showing our new design; FIG. 10 is a front elevation view thereof; FIG. 11 is a rear elevation view thereof; FIG. 12 is a left side elevation view thereof; FIG. 13 is a right side elevation view thereof; FIG. 14 is a top plan view thereof; FIG. 15 is a bottom plan view thereof; and, FIG. 16 is a front right perspective view of the container for a confectionery of FIG. 9, showing a portion of the lid portion thereof in an alternate position.

The broken lines represent environmental subject matter only and form no part of the claimed design. In the embodiment of FIGS. 9-16, the oblique shade lines shown on the body portion of the container for a confectionary represent translucent material that is also part of the claimed design.
